CLAIM

The ornamental design for a resin bubble remover machine, as shown and described.

DESCRIPTION

FIG. 1 is a top, front and right side perspective view of a resin bubble remover machine, showing my new design; FIG. 2 is a bottom, rear and right side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is an explosive perspective view of the resin bubble remover machine.

The evenly broken lines show the features of the resin bubble remover machine that form no part of the claimed design.

1 Claim, 9 Drawing Sheets
